UNITED STATES PATENT OFFICE.

WILLIAM TURNBULL, OF PEORIA, ILLINOIS, ASSIGNOR TO THE HOLT MANUFACTURING COMPANY, OF STOCKTON, CALIFORNIA, A CORPORATION OF CALIFORNIA.

GOVERNOR-CONTROLLED THROTTLE-VALVE.

1,344,362.

Specification of Letters Patent. Patented June 22, 1920.

Application filed September 1, 1917. Serial No. 189,403.

To all whom it may concern:

Be it known that I, WILLIAM TURNBULL, a citizen of the United States, residing at Peoria, in the county of Peoria and State 5 of Illinois, have invented new and useful Improvements in Governor-Controlled Throttle-Valves, of which the following is a specification.

This invention relates to governor controlled throttle valves for internal combustion engines.

In the ordinary governor controlled butterfly throttle valve the action of the suction from the engine creates a tendency on the 15 part of the valve when closed to remain closed until the suction resistance is overcome and then to open suddenly. This throws an unequal load on the governor and results in an irregular action.

20 The present invention has for its object to overcome these defects and the result is obtained by providing a throttle valve against which the suction of the engine always exerts a tendency to open same, such 25 valve being so weighted as to tend to close by gravity.

One form which my invention may assume is exemplified in the following description and illustrated in the accompanying 30 drawings, in which—

Figure 1 shows a side elevation of an engine fitted with a governor controlled throttle valve embodying my invention.

Fig. 2 shows a sectional view of the throttle valve.

The throttle valve here shown is preferably in the form of a weighted puppet-valve A, mounted on a stem B guided at its upper end in a spider C and having a beveled seat D from which the valve opens in a direction toward the engine. Preferably, the valve is arranged in the intake of the manifold E. The throttle valve is connected with the governor F in such a way that the 45 governor springs, or the normal action of the governor over-balances the weight of the valve and holds the latter open.

In operation, as the speed of the engine increases and the weights G on the governor 50 fly outwardly, the valve is correspondingly closed. The actuating connections as shown herein embody a shaft H having one arm I jointed to the lower end of the valve stem B and another arm J connected by a link 55 K to a governor arm L pivotel at M and

normally held inwardly at its upper end by means of a spring N. When the speed of the engine increases, the governor balls G, acting through suitable lever arms, draw the lower end of lever L inwardly against 60 the action of spring N.

Various changes in construction and arrangement of the several parts herein shown and described may be made without departing from the spirit of my invention as disclosed in the appended claims.

Having thus described my invention what I claim and desire to secure by Letters Patent is—

1. In an internal combustion engine, a 70 throttle valve tending normally to seat by reason of gravity and acted upon by suction from the engine to tend to open, and a governor for controlling said valve arranged so that the normal load on the governor 75 over-balances the weight of the valve and holds the latter open, further opening being assisted by suction, and closing of the same being assisted by gravity.

2. A governor controlled throttle valve 80 for internal combustion engines, comprising a weighted puppet-valve movable vertically, and a beveled seat below for said valve formed in the intake manifold, said valve by reason of its weight tending normally 85 to close, and being actuated by suction from the engine in a direction to produce a tendency to open, and a governor operatively connected to said valve in such manner that the normal load on the governor over-balances the weight of the valve and holds said 90 valve open.

3. A governor controlled throttle valve for internal combustion engines, comprising a weighted puppet-valve movable vertically, and a beveled seat below for said valve formed in the intake manifold, said valve by reason of its weight tending normally 95 to close, and being actuated by suction from the engine in a direction to produce a tendency to open, and a governor operatively connected to said valve in such manner that the normal load on the governor over-balances the weight of the valve and holds said valve open, said operative 100 connections including a shaft having an arm linked to the lower end of the stem of the valve, a second arm on the shaft, a link connected to said second arm, and a governor arm to which said link is connected 110.

nected, said governor arm being spring-pressed in a direction to tend to open said valve.

4. A governor controlled throttle valve mechanism comprising in combination with an internal combustion engine, an intake, a throttle valve normally tending on suction to remain open, a governor and direct connections between the governor and valve whereby on an increase of engine speed

beyond a predetermined point the governor operates correspondingly to close the valve.

In testimony whereof I have hereunto set my hand in the presence of two subscribing witnesses.

WILLIAM TURNBULL.
